(57) **CLAIM**

The ornamental design for an electric vehicle supply equipment, as shown and described.

DESCRIPTION

FIG. 1 is a front-right perspective view of an embodiment of an electric vehicle supply equipment;

FIG. 2 is a front view of the electric vehicle supply equipment of FIG. 1;

FIG. 3 is a rear view of the electric vehicle supply equipment of FIG. 1;

FIG. 4 is a left side view of the electric vehicle supply equipment of FIG. 1;

FIG. 5 is a right side view of the electric vehicle supply equipment of FIG. 1;

FIG. 6 is a top view of the electric vehicle supply equipment of FIG. 1;

FIG. 7 is a front-right perspective view with right side door open of the electric vehicle supply equipment of FIG. 1;

FIG. 8 is a front view with right side door open of the electric vehicle supply equipment of FIG. 1;

FIG. 9 is a rear view with right side door open of the electric vehicle supply equipment of FIG. 1;

FIG. 10 is a left side view with right side door open of the electric vehicle supply equipment of FIG. 1;

FIG. 11 is a right side view with right side door open of the electric vehicle supply equipment of FIG. 1; and,

FIG. 12 is top view with right side door open of the electric vehicle supply equipment of FIG. 1.

The broken lines shown in the drawings are included for the purpose of illustrating unclaimed portions of the electric vehicle supply equipment and form no part of the claimed design.
